(21) Appl. No.: **29/240,311**

(57) **CLAIM**

(22) Filed: **Oct. 11, 2005**

The ornamental design for a wheel hub cover for rotary air coupling, as shown and described.

(51) **LOC (8) Cl. 12-16**

DESCRIPTION

(52) **U.S. Cl. D12/213; D12/400**

FIG. 1 is a front, left side perspective view of the wheel hub cover for rotary air coupling, showing our new design;

(58) **Field of Classification Search D12/207, D12/213, 400, 604, 606-607; 301/108.1, 301/105.1; 152/415-417, 427-429**

FIG. 2 is a rear, right side perspective view thereof;

See application file for complete search history.

FIG. 3 is a top plan view thereof;

(56) **References Cited**

FIG. 4 is an end view thereof; and,

U.S. PATENT DOCUMENTS

FIG. 5 is a side view thereof.
